CLAIM

(21) Appl. No.: **29/458,445**

The ornamental design for a cylinder block for internal combustion engines, as shown and described.

(22) Filed: **Jun. 19, 2013**

DESCRIPTION

(30) **Foreign Application Priority Data**

Dec. 19, 2012 (JP) 2012-030985

FIG. 1 is a front elevation view of the cylinder block for internal combustion engines showing our new design;

(51) **LOC (10) Cl.** **15-01**

FIG. 2 is a rear elevation view of the cylinder block for internal combustion engines;

(52) **U.S. Cl.**

FIG. 3 is a right side elevation view of the cylinder block for internal combustion engines;

USPC **D15/5**

FIG. 4 is a left side elevation view of the cylinder block for internal combustion engines;

(58) **Field of Classification Search**

FIG. 5 is a top plan view of the cylinder block for internal combustion engines;

USPC ..... D15/1-5; 123/193.2, 195 R, 196 R,
123/41.84, 41.74

FIG. 6 is a bottom plan view of the cylinder block for internal combustion engines;

See application file for complete search history.

FIG. 7 is a front perspective view of the cylinder block for internal combustion engines as seen from the right upper side;

(56) **References Cited**

FIG. 8 is a front perspective view of the cylinder block for internal combustion engines as seen from the left lower side;

U.S. PATENT DOCUMENTS

FIG. 9 is a rear perspective view of the cylinder block for internal combustion engines as seen from the left upper side; and,

4,683,844 A * 8/1987 Arai et al. 123/41.74
4,712,517 A * 12/1987 Anno et al. 123/41.74
4,757,790 A * 7/1988 Ushio et al. 123/193.2
4,856,462 A * 8/1989 Ushio et al. 123/41.84
4,993,378 A * 2/1991 Sakurahara et al. ..... 123/196 R
5,462,108 A * 10/1995 Katoh et al. 164/98
5,537,969 A * 7/1996 Hata et al. 123/193.2
6,216,658 B1 * 4/2001 Pierro et al. 123/193.2

FIG. 10 is a rear perspective view of the cylinder block for internal combustion engine as seen from the right lower side.
